UNITED STATES PATENT OFFICE.

GEORGE G. RAMBAUD, OF NEW YORK, N. Y.

MACHINE FOR SEALING THE ENDS OF METALLIC TUBES.

1,026,456.

Specification of Letters Patent.

Patented May 14, 1912.

Application filed February 19, 1912. Serial No. 678,543.

To all whom it may concern:

Be it known that I, GEORGE G. RAMBAUD, a citizen of the United States, residing at New York, in the county of New York and 5 State of New York, have invented new and useful Improvements in Machines for Sealing the Ends of Metallic Tubes, of which the following is a specification.

This invention relates generally to machines for hermetically sealing or closing the ends of metallic tubes, by electrically soldering or welding the ends thereof, but is chiefly designed to seal the ends of that 10 variety of tubes commercially known as 15 "collapsible" tubes.

One of the principal objects of the invention is to provide an apparatus by means of which the operation of closing and sealing the ends of collapsible tubes may be efficiently and economically accomplished, and 20 with great rapidity.

With this and other objects in view, the invention consists in the general construction, arrangement and combination of the 25 several parts of the device, as hereinafter described, illustrated in the drawing, and more particularly pointed out in the claims 30 hereunto appended.

In the drawing: Figure 1 is a top plan view of the device, showing the electric circuit for supplying heat, and means for opening and closing said circuit; Fig. 2 is a vertical cross-section through the base and bed-plate, and shows the sealing mechanism in 35 elevation, and the manner of securing the same to said base and bed-plate; Fig. 3 is a section through the circuit closing mechanism, and Fig. 4 is a sectional detail of the sealing mechanism.

40 Referring to the several views, the numeral 1 indicates a suitable base, preferably composed of a metal frame, rectangular in shape, supported upon legs or supports 2, and provided with inwardly extending projections 3. Seated in the base is a bed-plate or block 4, of slate or other non-conducting material, and passing through suitable apertures therein, and directly opposite each other, are two posts or standards 5, 5, the 45 lower ends of which pass through perforations in the inwardly-extending projections 3, and being screw-threaded are secured in fixed position by nuts 6.

Adjustably secured on each post 5 is a collar 7, and above each collar is a coil-spring

8. Vertically movable on the posts 5, 5, above the springs 8, is a bar 9, to which is secured a plunger 10. The lower end of said plunger is screw-threaded, and the upper end thereof passes through a perforation in a bar 11, and is provided with a suitable head 12, said bar 11 having its ends secured to the posts 5, 5, as shown. Surrounding each post 5, between the bars 9 and 11, is a coil-spring 13, one end of which 60 is secured to the bar 11, and the other end to the bar 9, so that when the pressure necessary to force the plunger downward is removed, the action of the springs 8 will exert a pushing-force on the bar 9, and the springs 65 13 a pulling-force on said bar to return the plunger to its normally elevated position. The numeral 14 indicates a suitable bracket or holder, and is provided in its upper portion with a screw-threaded seat adapted to 70 receive and hold the lower screw-threaded end of the plunger 10, as shown; and in its lower portion is provided with a suitable seat adapted to receive and hold a suitable presser-block 15, of any non-conducting and 75 heat-resisting material, such as porcelain, said block 15 being secured in said bracket 14, by suitable securing means 16, 16, preferably set-screws, as shown. While I have 80 described the bracket 14 as being secured to the plunger by screw-threads, it is evident that said bracket may be made integral with said plunger, or secured thereto by other suitable means without departing 85 from the spirit of my invention. 90

The slate bed-plate 4 is provided with an anvil or block 17, of any suitable non-conducting and heat-resisting material, such as porcelain, and is, preferably, L-shape in cross-section, so as to provide a vertical abutment 18 for the purpose of gaging the extent of sealing of the flattened end of the tube. The anvil 17 is provided with a heater 19, preferably of a slightly flattened nickel-chrome wire, the ends of which are connected with binding posts 20, 20. 100

Situated at any convenient point on the bed-plate is an electric-switch 22, preferably of the usual knife type, the post 23 to which the blade 24 is pivoted, being secured in a 105 perforation passing through said bed-plate. The lower end of the post 23 is provided with clamping bars or plates 25, 25, between which the main line wire 26 is clamped by means of the nut 27 on the lower end of said 110

post 28, as shown. The post 28 with which the blade of the switch is adapted to make contact is in electrical communication with one of the binding posts 20 through the conductor 29, the other binding post 20, being connected with the other main line wire 30, both main line wires leading to a suitable source of electrical supply, as shown.

In operating my invention I take a tube 10 which has, preferably, been filled, and place the end thereof, which has been flattened in the usual way, upon the horizontal portion of the anvil, resting on the heater, with its flattened end abutting against the vertical portion 18 of said anvil; the switch is then closed and the current will pass over conductor 29 to the heater; pressure is then applied to the plunger to force the presser-block into contact with the end of the tube 15 resting upon the heater to effect the sealing by the heat generated in said heater. As soon as the sealing is completed, which is done almost instantly, pressure is removed 20 from the plunger which is immediately returned to normal position by the action of said springs. The sealed tube is then removed and another placed in position for sealing, when the operation is repeated. It will be observed that the ends of the tubes 25 30 may be flattened between the porcelain blocks just before the current is turned on, and the sealing effected by one and the same operation. It will also be evident that in sealing the ends of tin collapsible tubes 35 40 a soldering agent will not be necessary, as the tin coating will serve as an efficient uniting agent; but when the ends of plain metal tubes are to be soldered a small quantity of solder may be used as the uniting agent. It will also be obvious that the heating circuit may be automatically closed and opened by the fall and rise of the plunger by connecting the switch therewith, either by lever, or otherwise.

Having thus described my invention what 45 I claim, is:

1. A machine for soldering the ends of metal tubes, comprising a fixed anvil of heat-resisting material provided with an electric heater, a gage-stop integral with 50 said anvil for determining the width of the seam to be soldered, a pressure-block, means for moving said pressure-block, means for supplying a current of electricity to the heater, and a suitable electric switch. 55

2. A machine for sealing the ends of metal tubes, comprising a fixed anvil of porcelain provided with an electric heater, a gage-stop integral with said anvil for limiting the width of the seam to be soldered, a plunger carrying a porcelain presser-block, said plunger being attached to a horizontal bar vertically movable on a pair of supports, compressible springs adapted to return the plunger to normal position after having 60 been depressed, and means for supplying a current of electricity to the heater. 65

3. A machine for sealing the ends of metal tubes, comprising a fixed porcelain anvil provided with an electric heater, a gage-stop integral with said anvil for limiting the width of the seam to be soldered, means for supplying a current of electricity to the heater, a plunger attached to a horizontal bar vertically movable upon supporting-posts, a porcelain presser-block carried by the plunger, compressible and expandible springs for returning the plunger to normal position after having been depressed, and means for opening and closing the electric 70 75 80 circuit.

In testimony whereof I have hereunto set my hand in presence of two subscribing witnesses.

GEORGE G. RAMBAUD.
